(57) **CLAIM**

The ornamental design for a heated spatula, as shown and described.

DESCRIPTION

FIG. 1 is a front view of a heated spatula according to the present invention, the rear view is a mirror image of the front view;

FIG. 2 is a right side view thereof, wherein the portions of the drawings shown in broken lines, e.g., the broken line charging port, are for illustrative purposes only and form no part of the claimed design;

FIG. 3 is a left side view thereof, wherein the portions of the drawings shown in broken lines, e.g., the broken line on-off switch, are for illustrative purposes only and form no part of the claimed design;

FIG. 4 is a top view thereof; and,

FIG. 5 is a bottom view thereof.

The broken lines in the drawings depict environmental subject matter only and form no part of the claimed design.
